(57) **CLAIM**

We claim the ornamental design for a remote controller for air conditioning equipment, as shown and described.

DESCRIPTION

FIG. 1 is a front, top and left side perspective view of a remote controller for air conditioning equipment showing our new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a rear elevational view thereof; and,

FIG. 8 is a cross-sectional view taken along line 8-8 in FIG. 2.

The broken lines shown in the drawings represent portions of the remote controller for air conditioning equipment that form no part of the claimed design.
